(57) **CLAIM**

The ornamental design for a medical syringe adapter, as shown.

DESCRIPTION

FIG. 1 is a perspective view of a medical syringe adapter showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Portions of the medical syringe adapter shown in dashed lines in FIGS. 1 and 4-7 depict unclaimed portions of the medical syringe adapter that are included for environmental purposes only.

1 Claim, 6 Drawing Sheets(56)
